UNITED STATES PATENT OFFICE.

WILLIAM S. ROGERS, OF CLEVELAND, OHIO, ASSIGNOR TO J. C. PEARSON COMPANY, OF BOSTON, MASSACHUSETTS, A CORPORATION OF MAINE.

VENTILATING SYSTEM.

SPECIFICATION forming part of Letters Patent No. 761,405, dated May 31, 1904.

Application filed September 8, 1903. Serial No. 172,196. (No model.)

To all whom it may concern:

Be it known that I, WILLIAM S. ROGERS, a citizen of the United States, residing at Cleveland, in the county of Cuyahoga and State of Ohio, have invented a new and useful Improvement in Ventilating Systems, of which the following is a specification.

This application relates to a system of ventilation which is particularly adapted for buildings in which volatile liquids are employed; and it consists in a series of blowpipes which are so positioned and directed as to create a thorough agitation of the gaseous contents of the building near the floor, the said contents being discharged from suitable openings at or near the top of the building.

In the accompanying drawings, Figure 1 is a longitudinal section through a building, taken on the line 1 1 of Fig. 2 and showing my ventilating system in use in a nail-coating plant. Fig. 2 is a transverse section through the building, taken on the line 2 2 of Fig. 3; and Fig. 3 is a plan view taken substantially on the line 3 3 of Fig. 2, the partition through the building being removed.

In view of the fact that the vapors of gasoline and some other volatile liquids is heavier than air it naturally settles to the floor, where it mixes with the air and besides being oppressive and injurious to the workmen in the room it forms a mixture which may become highly explosive. In view of this fact it becomes very desirable to install in such places a ventilating system which will operate to remove these vapors from all parts of the building and which will furnish fresh and pure air thereto. A system for accomplishing this result is shown in the accompanying drawings, which, as stated, illustrate in connection therewith a plant for coating nails, in which plant the nails are placed in the buckets 1 and are lifted therein by means of cranes 2 and are then lowered into dipping tanks or vats 3, said vats containing a volatile liquid 45 as an ingredient of the coating solution.

When the nails are thoroughly drenched with the solution, the buckets are elevated and the nails are deposited upon the upper parts of the evaporators or conveyers 4. These

evaporators are inclined, as shown in Fig. 1, 50 and are also shaken back and forth, so as to cause the nails to gravitate or slide downwardly thereon and drop from the lower ends. While thus spread upon the evaporators or conveyers the volatile ingredients of the solution evaporate and leave the nails with a very thin film of coating. This evaporating process is hastened by directing a blast of air upon the evaporator, as will be hereinafter explained. The air for ventilating and for drying the nails is furnished by a blower 5, which may take the air from the outside of the building or from the room which is partitioned off from that in which the evaporation takes place, as is shown in Figs. 1 and 3, in which 55 there is a partition 6. The air that is thus furnished is forced upwardly through the large supply-pipe 7 to a point 8, where the pipe divides into two branches, the branch 9 extending substantially in line with pipe 7 60 along the side of the building and the other, 10, passing transversely across the room to a point near the opposite side, where it turns also and extends along the side of the building parallel with the pipe 9. At intervals 65 throughout the length of the pipe 9 there are small blowpipes 11, that are bent downwardly and inwardly, so as to direct the air that issues therefrom across the room, so that it will strike the floor toward the opposite side of 70 the building, as indicated by the arrows in Fig. 2. A similar series of blowpipes 12 are connected with the pipe 10, said blowpipes also extending downwardly and inwardly, so as to direct the air that issues from them toward 75 the opposite side of the floor, the direction of said blast of air also being indicated in Fig. 2. While this figure shows but one row of arrows, it will be understood that the air is diffused as it emerges from the pipe, so that 80 the air from one of the pipes is scattered over the half of the floor which is on the opposite side of the building therefrom. After the air strikes the floor it rises, as indicated by 85 the arrows, and is forced outwardly through 90 the ventilator 13 on the top of the building. This ventilator may be of any suitable form; but it should extend the entire length of the 95

building or at least of the entire length of the evaporating-room. As shown, the sides of the ventilator are formed of slats 14, that are inclined to prevent the entrance of rain, 5 the spaces 15 between the slats affording sufficient room for the gases to pass out. To more effectually shut out the rain, the edges of the slats are bent vertically, as shown in Fig. 2.

10 In order to more effectually cover the floor-space of the building and to prevent the blast from pipes 11 interfering with those from the pipes 12, I have placed the pipes in alternate arrangement, those on one side being opposite the spaces between the pipes on the other side. The blasts of air for evaporating the coating solution on the nails is furnished by the pipes 9 and 10, the pipe 9 being carried across the end of the room and terminating 15 over the evaporator 4, as shown in Fig. 3. The end of the pipe is bent downwardly toward the evaporator, as shown at 16, and it is so positioned and shaped as to cause the air issuing therefrom to cover as nearly as possible 20 the entire surface of the evaporator. A similar pipe 17 is directed downwardly from the pipe 10, so as to furnish a blast for evaporating the nails on the other evaporator 4.

The blower 5 is driven by means of the 25 motor 18, that is connected by suitable gearing therewith. The capacity of the blower is so proportioned with that of the building that the latter is quickly emptied of all of its air and vapors, said air being entirely changed 30 within a space of a very few minutes; otherwise the vapors will accumulate and the air will become charged with them to the danger-point.

While I claim my invention as especially 35 adapted for use in buildings where volatile liquids are employed, I do not wish it to be understood that I deem it limited entirely to such uses, as it is evidently adapted for more general use. The nail-coating plant is herein 40 shown and described for the purpose of a clearer description and as showing some plant to which my invention is especially adapted.

Having thus described my invention, what 45 I claim as new, and desire to secure by Letters 50 Patent, is—

1. In a ventilating system for a building, a tube that is located above the floor, a series of pipes connected with said tube and extended at an angle to the said floor toward a portion 55 thereof near the side wall of the building, a passage for gases in the upper part of the building, and means for blowing the air through the tube and pipes to cause the air and gases next the floor to rise and pass out 60 through the said passage.

2. In a ventilating system for a building, a tube that is located above the floor and near one side of the building, a series of pipes connected with said tube and opening in the di-

rection of the floor near the opposite side of the building, a passage for gases in the upper part of the building, and means for blowing air through the tube and pipes, to cause the air and gases next the floor to rise and pass out through the said passage. 65

3. In a ventilating system for a building, a pair of tubes that are located above the floor and near each side of the building respectively, a series of pipes connected with said tubes, said pipes opening in the direction of the floor 70 at points near the opposite side of the building, a passage for gases in the upper part of the building, and means for blowing air through the tubes and pipes to cause the air and gases next the floor to rise and pass out through said passage. 75

4. In a ventilating system for a building, a main tube, a pair of branch tubes connected therewith and passing along near the sides of the building above the floor thereof, a series 80 of pipes connected with each of said tubes, said pipes opening in the direction of the floor near the opposite sides of the building therefrom respectively, a passage for gases in the upper part of the building, and means for blowing the air through the tubes and pipes to cause the air and gases next the floor to rise and pass out through said passage. 85

5. In a ventilating system for a building, a pair of tubes that are located above the floor 90 and near the opposite sides of the building, a series of pipes 11 connected with one of said tubes, and a similar series of pipes 12 connected with the other tube, said pipes 11 and 12 being placed in alternate arrangement with 95 one another, and being extended in the direction of the floor near the side opposite thereto, for the purpose specified. 100

6. In a nail-coating plant, an evaporator on 105 which the nails are spread, a tube located above said evaporator, and extending along near the side of the building, a pipe connected with said tube and extending toward the evaporator, and a series of pipes connected with the tube along the side of the building, said latter pipes extending in the direction of the floor near the opposite side of the building, a passage for gases in the upper part of the building, and means for blowing the air 110 through the tube and the pipes to dry the nails and to cause the air and gases next the floor to rise and pass out through the said passage. 115

7. In a nail-coating plant, evaporators upon 120 which the nails are spread, a main tube, a pair of branch tubes connected therewith and extending along the opposite sides of the building, pipes connected with the said tubes and opening above the evaporators, a series of pipes 11 and 12 connected with the said tubes along the sides of the building, said pipes 125 opening in the direction of the floor near the sides of the building opposite thereto, a passage for gases in the upper part of the build-

ing, and means for blowing air through the tubes and pipes to dry the nails on the evaporators and to cause the air and gases next the floor to rise and pass out through the said passage.

8. In a nail-coating plant, evaporators upon which the nails are placed, a main tube, a pair of branch tubes connected therewith and extending along near the opposite sides of the building, pipes connected with the said tubes and opening above the evaporators, a series of pipes 11 connected with one of said tubes and a series of pipes 12 connected with the other tubes, said pipes 11 alternating in arrangement with the pipes 12 and each series of pipes being directed toward the floor at points near the side opposite thereto, a passage for gases in the upper part of the building, and means for blowing air through the tubes and pipes to dry the nails on the evaporators and to cause the air and the gases next the floor to rise and pass out through the said passage.

9. In a nail-coating plant, means for holding the nails while drying, a tube that is located above the floor, a series of pipes connected with said tube and extending at an angle to the said floor toward a portion thereof near the side wall of the building, a passage for gases in the upper part of the building, and means for blowing air through the tube and pipes to cause the air and the gases given off

while the nails are drying to rise and pass out through the said passage.

10. In a nail-coating plant, means for holding the nails while drying, a tube extending along near the side of the building, a pipe connected with said tube and extending toward the nail-holding means, a series of pipes connected with the tube along the side of the building, 40 said latter pipes extending in the direction of the floor near the opposite side of the building, a passage for gases in the upper part of the building, and means for blowing the air through the tube and pipes to dry the nails 45 and to cause the air and gases next the floor to rise and pass out through the said passage.

11. In a nail-coating plant, means for holding the nails while drying, a tube that extends substantially parallel with the floor of the 50 building, a series of pipes connected with said tube and opening toward a portion of the floor near the side wall of the building, a passage for gases in the upper part of the building, and means for blowing air through the tube 55 and pipes to cause the air and the gases given off while the nails are drying to rise and pass out through the said passage.

In testimony whereof I affix my signature in the presence of two witnesses.
